UNITED STATES PATENT OFFICE.

FRANCIS M. VANDERVOORT, OF PUEBLO, COLORADO, ASSIGNOR TO THE POSITIVE LOCK COMPANY, OF PUEBLO, COLORADO, A CORPORATION OF COLORADO.

LATCH AND KEEPER MEANS.

Application filed July 12, 1923. Serial No. 651,112.

This invention relates to latch and keeper means, and relates more particularly to latch and keeper means used in connection with doors of vehicles such as automobiles although the invention is not limited to this particular use. The term latch is used broadly to include both lock and latch constructions.

It is very difficult to prevent the doors of an automobile from rattling when the automobile is operated. Twisting of the automobile frame and body, slamming of the doors, and the vibration of the automobile in motion ordinarily cause the latch and keeper parts and the doors to loosen up and rattle in a very short time.

An object of this invention is to provide latch means in which all movable parts are held against rattling no matter how loosely these parts may be fitted or how much they may wear.

Another object of the invention is to provide keeper means which will readily yield to receive the latch bolt, making slamming of the door to engage the latch bolt in the keeper unnecessary, said keeper means firmly holding the latch bolt against rattling.

A further object of the invention is to provide latch and keeper means of simple but rugged construction which can be cheaply manufactured.

Other objects and features of the invention will be apparent from the following description taken in connection with the accompanying drawings which show one specific embodiment of the invention, but it is to be understood that the specific embodiment of the invention shown and described is merely one form typical of the broad invention chosen to explain the principles of the broad invention and is to be taken as illustrative and not restrictive.

In the drawings,

Fig. 1 is a side elevational view of latch and keeper means embodying this invention shown in the position which the parts thereof occupy when mounted on the door and door jamb, respectively, of an automobile, part of such door and door jamb being shown in dotted lines. Part of the casing of the keeper means is shown in cross-section.

Fig. 2 is a sectional view taken on the line 2—2 of Fig. 1 looking in the direction of the arrows. The section of the keeper means is taken on line 2—2 of Fig. 4 looking in the direction of the arrows.

Fig. 3 is a sectional view taken on the line 3—3 of Fig. 1 looking in the direction of the arrows.

Fig. 4 is a plan view of keeper means embodying the invention with one of the cover plates removed, showing the latch bolt, illustrated in section, in position in the keeper means.

Fig. 5 is a view similar to Fig. 4 showing the bolt, illustrated in section, entering the keeper means.

Fig. 6 is an end view of the latching means.

Fig. 7 is a sectional view on line 7—7 of Fig. 2 looking in the direction of the arrows, and

Fig. 8 is a fragmentary sectional view taken on line 8—8 of Fig. 1 looking in the direction of the arrows.

Generally stated, the present invention comprises a latch adapted to be mounted on a door, such as the door of an automobile, the latch having a normally projecting bolt that engages in and is held in latched position by keeper means mounted in the door jamb, the keeper means yielding to receive and latch the bolt when the door is closed. To open the door, the latch bolt is withdrawn laterally from within the keeper means. In its latched position, the projected bolt is clamped against all lateral movement in the latch mounting or casing and the keeper means has elements which clamp and hold the latched bolt against rattling in the keeper means.

Referring to the drawings, 10 indicates generally the latch mounting or casing which may be of any desirable shape and construction to support the latch parts, although the construction illustrated is especially desirable, especially from the standpoint of reducing manufacturing costs. As shown, the mounting 10 comprises a base or back plate 11 provided with holes 12 to receive suitable fastening means such as screws or rivets for securing the latch to the door, indicated in dotted lines at D. Base plate 11 has an

integral angular extension 13 at one end to form the front face of the mounting or casing, the extension being designed to lie flush in the free or swinging edge of the door. 5 Extension 13 is provided with a hole 14 to permit passage of the bolt B therethrough. Secured to base or back plate 11 is a housing plate 15. In the present instance housing plate 15 comprises an integral piece of 10 sheet metal bent to form sides 16, 17, 18 and end 19 of a bolt guiding and housing chamber indicated generally by 151; and side 20 and end 21 of a housing for the bolt-operating parts of the latch. Housing plate 15 15 may be secured to base or back plate 11 by any suitable means, but the securing means shown is preferred since it eliminates the use of rivets or screws. As illustrated, housing plate 15 is provided with lugs 22 which 20 extend through cooperating apertures 23 in the back plate 11, the lugs being bent over to securely hold the two plates together. Housing plate 15 is connected to front plate or extension 13 by a bent lug or tongue 221 25 extending into an aperture or socket 231 provided in plate 13. The bolt B is supported and guided for sliding movement in the bolt chamber 151 formed by back plate 11 with its extension 13 and sides 16, 17, 18 30 and end 19 of housing plate 15. It will be noted, as seen in Fig. 2, that side 17 of the bolt chamber 151 does not extend over so far as the front plate 13, leaving that side of the bolt chamber open at the front end. 35 Sides 16 and 18 of the bolt chamber are each provided at the points where these sides adjoin front plate 13 with projecting lugs or tongues 38 which are bent to overhang the sides of the channel bolt B to form guides or 40 bearing surfaces for the latter. As shown in Fig. 6, the hole 14 provided in front plate 13 to afford a passage for bolt B therethrough is made large enough to receive lugs or tongues 38 whereby plate 13 and 45 lugs 38 are mutually braced and supported. Bolt B may be of any suitable construction, but the construction illustrated is preferred because such a bolt may be cheaply made of stamped sheet metal. In the present instance, bolt B is U or channel-shaped, 50 having a web 24 and flanges or sides 25 and 26. As stated previously, bolt B is supported for sliding movement in the bolt chamber, the projecting or forward end of 55 the bolt extending through aperture 14 in the front plate or extension 13. Intermediate the ends of bolt B a tongue 27 is punched or struck out from the web 24 of the channel bolt, tongue 27 bearing against 60 back plate 11 to form a bottom guiding or bearing surface for the bolt. Tongue 27 also forms an abutment to be engaged by the bolt retracting means which will be explained hereafter. Special guiding means 65 are provided for the rear or inner end of the bolt. The flanges or sides 25 and 26 at the inner or rear end of bolt B are bent in toward each other at 28 and 29, respectively, so that the edges of the flanges or sides of the channel bolt are oppositely inclined relatively to each other. (See Fig. 3.) Side 17 of the bolt chamber 151 is bent in to provide a projection 30 having oppositely inclined or bevel portions 31 extending into the bolt chamber and between the oppositely inclined bearing or guiding portions 28 and 29 of flanges or sides 25 and 26 of the channel bolt B. Projection 30 with its oppositely inclined walls or bevel portions 31 cooperates with bearing portions or guides 28 and 29, projection 30 acting as a wedge to hold bolt B against all lateral movement when bolt B is pressed thereagainst. Suitable means are provided for normally holding the bolt in projected position and in the example illustrated a spring 32 mounted between the rear or inner end of bolt B and end 19 of the casing is provided for this purpose. The web at the rear or inner end of the bolt B is cut away for a short distance to provide a socket or recess 33 to receive and support the spring against slipping. 70 75 80 85 90 95 100 105 110 115 120 125 130

Means to clamp the bolt against lateral movement in the latch casing when the bolt is projected are provided. Intermediate its ends, the bolt B is provided with a bevel or inclined portion 34. In the example illustrated the bolt is bent to form the bevel or inclined portion, but it is obvious that the bevel portion could be cast on or cut out of the bolt within the broad scope of the invention. The bevel portion 34 of the bolt engages suitable abutment means or stops 35 to wedge the bolt in the casing against lateral movement when the bolt is projected.

Referring to Fig. 7, it will be noted that in the present instance there are two abutment members or stops and that each abutment member or stop 35 comprises a base portion 36 and an inclined end portion 37. The inclined end portion 37 is inclined longitudinally with relation to the bolt to correspond to the inclined portion 34 of the bolt. The inclined end portions 37 of the abutments or stops 35 are also inclined laterally of the bolt and in this instance the end portions are oppositely inclined relatively to each other and to the web of the bolt and it will be observed that the bolt extends between and engages the oppositely inclined end portions of the abutments or stops when the bolt is projected. The abutments or stops 35 act to limit outward movement of the bolt B and when the bolt engages the abutments or stops, the bolt is moved laterally and wedged between the abutments or stops and clamped against the opposite bolt guides. When the bolt B is in the projected position the inclined abutments or stops 35

wedge the bolt against the overhanging bent portions or guides 38 at the front end of the bolt and against the inclined portions or guides 31 provided in the bolt housing at the rear end of the bolt. It will be noted that in view of the fact that the abutment members and guides for the bolt are oppositely inclined transversely of the bolt, the bolt is clamped against all lateral movement when it is projected. The abutment members or stops 35 may be constructed in any suitable manner, but in the present instance, the abutment members are made integral with the back plate 11 and are formed from tongues cut or struck out from the back plate.

Any suitable means for retracting the bolt may be provided. In the present instance, a lever 39 pivoted at 40 to the latch casing 20 is provided, the lever extending up to or slightly above the top of the door to which the latch is mounted. The operating lever 39 is pressed by spring means 41 into engagement with a roll back or cam 42 pivoted 25 at 43 to the latch casing. While any type of spring may be used, the type illustrated is preferred. In the present instance, spring 41 is a plate spring having a bent portion 44 at one end hooking over a lug or tongue 30 45 struck out from the back plate 11. The other end 46 of the spring engages the pivoted lever 39 to hold the latter in engagement with the cam or roll back 42 and thus prevent rattling of both the lever and roll-back. Lever 39 is adapted to engage the tongue or guide 27 provided intermediate the ends of the bolt B to retract the bolt as 40 previously explained. With the parts in their normal position, lever 39 is spaced away from the tongue 27 so that the lever will not engage the bolt and prevent projection and consequent clamping of the bolt. Roll-back 42 is provided with a square aperture 47 to be engaged by the shank of an 45 outside handle not shown. When the handle is turned, it will swing the roll-back 42 which in turn will swing the lever 39 to retract the bolt. Any suitable means of pivoting the lever and roll-back to the latch casing 50 may be provided, but the means shown is preferred from the standpoint of reducing manufacturing costs. As shown in Fig. 8, the roll-back and lever are each provided with an extruded portion 48 and a socket 49. 55 In each case, the extruded portion 48 is fitted in an aperture 50 provided in one of the plates of the casing and the other plate is provided with a hollow extruded portion 51 engaging in the socket 49 of the roll-back 60 or lever as the case may be. It will be noted that the latch is composed of a minimum number of parts and that these parts can all be made of sheet metal bent by stamping operations to assume their proper shape. 65 The use of rivets, bolts, screws or other

means to connect the parts is entirely eliminated.

The outer end of the bolt normally projects from the free edge of the door to which the latch is mounted and when the door is 70 moved to closed position, the bolt engages within suitable keeper means which hold the bolt in latched position. No retraction of the bolt takes place when it moves to latched position, the keeper means yielding to receive and hold the bolt in latched position. The keeper means is mounted within a suitable mounting or casing comprising two plates 52 and 53. In the present instance, each of the plates 52 and 53 is provided with 75 integral right angular extensions to form sides and ends. The casing members 52 and 53 are held together by any suitable means, but the securing means shown is preferred 80 since it serves the double function of holding 85 the plates together and also providing apertures for the insertion of rivets, screws or other means for securing the casing to the door jamb J. As shown in Fig. 1 one of the casing plates, in this instance plate 52 is provided with a hollow extruded portion 52^a and the other plate, in this instance plate 53, is provided with a corresponding hollow extruded portion 53^a extending into the 90 co-operating extruding portion on plate 52, the 95 projecting end of the extruded portion of plate 53 being expanded or riveted to hold the two plates together. A counter-sunk aperture is thus provided to receive suitable fastening means as previously explained. 100

Mounted between the casing members 52 and 53 are provided means for latching the bolt B and for clamping the bolt against rattling in the keeper means. 105

Referring especially to Figs. 4 and 5, mounted within the casing members 52 and 53 are two opposed hook-shaped latching members 54 and 55 pivoted at 56 and 57 respectively. The hook ends 58 and 59 respectively of the members 54 and 55 are disposed adjacent one side of the casing of the keeper means and extend into a slot or recess 60 provided in the keeper casing, the latch or hook members being pressed or urged toward each other by suitable spring means. In the present instance, the hook members 54 and 55 are pressed toward each other by coiled springs 61 and 62, respectively, each spring extending between an end of the casing and its respective hook member, the hook members each being provided with a seat 63 to receive an end of one of the springs. The opposed edges of the hook members 54 and 55 are formed to provide recesses or indentations 64 and 65 respectively. These indentations or recesses provide a support or cradle for a movable abutment member 66. Abutment member 66 is provided with a 115 face 67 conforming substantially to the con- 120

tour of the bolt B and with circular or curved end portions 68 and 69 engaging in the recesses or indentations 64 and 65 respectively of the hook members 54 and 55. Abutment member 66 is also provided with a lateral projection 70 which extends between the pivoted ends of the hook members, said pivoted ends forming guides to support and to permit sliding movement of the abutment member between the pivoted ends of the hook members. Swinging of the hook members causes a sliding movement of the abutment member. It will be observed that abutment member 66 also forms a stop or abutment to prevent the hook members from swinging together or closing so far that entry of the bolt into the keeper would be prevented. In the example illustrated, hook members 54, 55 and abutment 66 are of laminated construction each element being made of two sheets or layers of metal although it is obvious that each of these elements could be made of more than two sheets or plates or each element could be made in one piece.

As shown in Fig. 5, when the door is moved to closed position, the bolt B, shown in cross section, will engage the curved surfaces 58^a and 59^a of the hook ends 58 and 59, respectively, to separate the opposed pivoted hook members 54 and 55. This causes the sliding movement of abutment member 66 away from the entering bolt due to the engagement of the ends 68 and 69 of the abutment member in the cam recesses or indentations 64 and 65 respectively of the hook members 54 and 55. When the bolt has been moved so that the bolt is entirely between the hook members 54 and 55, the hook members will swing toward each other, hook ends 58 and 59 moving to overhang and hold the bolt in latched position. As the hook members swing toward each other, abutment member 66 is moved toward the latch bolt, sliding movement of the abutment member 66 continuing until the abutment member engages and clamps the bolt against the hook ends 58 and 59 of the hook members. It will thus be seen that when the bolt is in latched position, it is clamped against rattling and that the bolt is clamped at all times when in the latched position, irrespective of wear of the parts.

While any suitable means for pivoting the latch members to the casing may be used, the means illustrated is preferred. As illustrated in Fig. 2, each hook member, which in the present instance is shown made of two pieces is provided with an extruded portion 71 and a socket portion 72. One of the casing plates, in this case the casing plate 52 is provided with an aperture 73 adapted to receive an extruded portion 71 and the opposite plate, in this case plate 53 is provided

with a hollow extruded portion 74 engaging 65 in a socket 72 of one of the hook members. In this manner, the use of pins or rivets as pivot points for the hook members is eliminated and the means for pivoting the hook members may be made in a stamping 70 operation.

While a latch bolt of channel shape has been shown and hook members shaped to cooperate with the channel shaped bolt have been shown, it is obvious that these parts 75 may be differently shaped. Other modifications within the scope of the invention will be obvious to those skilled in the art and it is to be understood that the invention is not limited to the exact arrangements illustrated 80 and described.

What I claim is:

1. The combination, with a bolt, of latching means therefor projecting in the path of said bolt movable to allow the bolt to pass 85 and then movable to prevent the bolt re-passing, and abutment means engageable by said bolt, said latching means provided with cam means engaging said abutment means to press said abutment means against said bolt 90 whereby said abutment means presses against and holds the bolt in engagement with said latching means.

2. The combination, with a bolt, of latching means therefor comprising means projecting in the path of the bolt yieldable to allow the bolt to pass and then movable to overhang the bolt and prevent its passage in the opposite direction, and cam operated abutment means engaging and pressing said bolt against said latching means. 95

3. The combination, with a bolt, of latching means therefor movable by said bolt and adapted to hold the latter in latched position, and a slidably abutment operable by 100 said latching means to hold said bolt in engagement with said latching means.

4. The combination, with a bolt, of latching means therefor movable by said bolt and adapted to hold the latter in latched position, and an abutment supported by and slidably connected to said latching means, said abutment pressing said bolt against said latching means. 110

5. The combination, with a bolt, of latching means therefor comprising members resiliently pressed one toward the other and separable by entry of the bolt therebetween, and an abutment, said abutment being embraced by and supported between said members whereby said abutment presses said bolt against said members. 115

6. The combination, with a bolt, of opposed members resiliently pressed one toward the other and adapted to latch said bolt therebetween, and a movable abutment, opposed edges of said opposed members engaging said abutment whereby the abut- 125

ment is supported between said members, said abutment limiting the movement of one opposed member toward the other.

7. The combination, with a bolt, of latching means therefor comprising a movable abutment, and a hook member, said bolt being movable past the hook end of said member to latch the bolt in the space between said hook end and said abutment, said hook member provided with cam means engaging said abutment, said abutment pressing said bolt against said hook end.

8. A device of the class described comprising opposed members separable one from the other by the insertion of a bolt therebetween, and an abutment engageable by a bolt entering between said members, one of said members provided with cam means engaging said abutment to press said abutment against said bolt, said abutment pressing the bolt against said opposed members.

9. A device of the class described comprising opposed members separable one from the other by the insertion of a bolt therebetween, and an abutment engageable by a bolt entering between said members, said abutment being supported for sliding movement by said members, said abutment operable by said members to engage the bolt and press the same against said opposed members.

10. A device of the class described comprising opposed members separable one from the other by the insertion of a bolt therebetween, and a slideable abutment engageable by a bolt entering between said members, said abutment pressing said bolt against said members.

11. A device of the class described comprising opposed members separable one from the other by the insertion of a bolt therebetween, and abutment means supported by said opposed members engageable by a bolt entering between said opposed members, said opposed members provided with cam means engaging said abutment means to press said abutment means against said bolt, said abutment means pressing the bolt against said opposed members.

12. A device of the class described comprising opposed members separable one from the other by the insertion of a bolt therebetween, said opposed members each provided with a recess, and an abutment engaging in such recesses engageable by a bolt entering between said members, said abutment pressing the bolt against said opposed members.

13. A device of the class described comprising opposed members separable one from the other by the insertion of a bolt therebetween, and an abutment engageable by a bolt entering between said members, said members formed to provide a cradle embracing and supporting said abutment whereby when the members are separated by the en-

tering bolt, the abutment is moved away from the bolt and when the members are forced together to engage the bolt, the abutment engages the bolt and presses the same in engagement with said members.

14. A device of the class described comprising opposed members separable one from the other by the insertion of a bolt therebetween, and an abutment engageable by a bolt entering between said members, the opposite edges of said opposed members being shaped to provide camming indentations receiving said abutment whereby the abutment is moved toward or away from the bolt as the opposed members are moved toward or away from the bolt.

15. A device of the character described comprising opposed members separable one from the other by the insertion of a bolt therebetween, spring means urging said members toward one another, and an abutment engageable by a bolt entering between said members, one of said members formed to provide cam means engaging said abutment to press said abutment against the bolt, said abutment pressing the bolt against the opposed members.

16. A device of the character described comprising opposed pivoted hook members separable one from the other by the insertion of a bolt therebetween, and an abutment engageable by a bolt entering between said members, said opposed members formed to provide cam means engaging said abutment to press said abutment against the bolt, said abutment pressing the bolt against the opposed members.

17. A device of the character described comprising opposed members separable one from the other by the insertion of a bolt therebetween, and an abutment engageable by a bolt entering between said members, said abutment being slidably connected to said opposed members whereby when said members are separated by the entering bolt, the abutment is moved away from the bolt and when the members are forced together to engage the bolt, the abutment engages the bolt and presses the same against said members.

18. A device of the character described comprising opposed pivoted hook members separable one from the other by the insertion of a bolt therebetween, spring means urging said members toward one another, and a sliding abutment engageable by a bolt entering between said members, said members being provided with cam means engaging said abutment to press said abutment against the bolt, said abutment pressing the bolt against the opposed members.

19. A device of the character described comprising opposed pivoted hook members separable one from the other by the insertion of a bolt therebetween, spring means urging

said members toward one another, and an abutment engageable by a bolt entering between said members, each of said members formed to provide a cam recess receiving 5 said abutment, said abutment engaging the bolt and pressing the same against said members.

20. A device of the character described comprising opposed pivoted hook members 10 separable one from the other by the insertion of a bolt therebetween, spring means urging said members toward one another, and a slid able abutment engageable by a bolt entering between said members, the opposite 15 edges of said opposed members being formed to provide camming indentations, the abutment engaging in said indentations whereby the abutment is supported between said members.

20 21. A device of the character described comprising opposed pivoted members separable one from the other by the insertion of a bolt therebetween, and an abutment engageable by a bolt entering between said 25 members, said abutment engaging said pivoted members intermediate their pivoted and swinging ends whereby the abutment is supported between said pivoted members, said abutment provided with a projection extending between the pivoted ends of said 30 members, said pivoted ends forming guides to permit sliding movement of said abutment.

22. A latch comprising, a casing, a bolt 35 carried by said casing, means normally projecting said bolt from said casing, and means carried by said casing for clamping said bolt against substantially all lateral movement when the bolt is projected.

40 23. In a latch, the combination with a bolt, of means normally projecting said bolt, and means at both ends of said bolt clamping the bolt against all lateral movement when the bolt is projected.

45 24. A latch comprising a casing, a bolt normally projecting from said casing, and means for clamping said bolt in said casing against all lateral movement when the bolt is projected.

50 25. A latch comprising a casing, and a bolt, bent to provide a bevel portion, normally projecting from said casing, said casing provided with means cooperating with said bevel portion to clamp said bolt against lateral movement when the bolt is projected.

55 26. A latch comprising a casing, a bolt bent to provide a bevel portion normally projecting from said casing, one of the walls of said casing provided with cam means engaging said bevel portion when the bolt is projected to wedge said bolt against the opposite wall of said casing to thereby clamp the bolt against lateral movement.

60 27. In a latch, the combination, with a bolt provided with a bevel portion, of a casing

providing guides for said bolt, means normally projecting said bolt from said casing, and means engaging said bevel portion when the bolt is projected and cooperating with said guides to clamp the bolt against all 70 lateral movement when the bolt is projected.

28. In a latch, the combination, with a bolt provided with a bevel portion, of a casing 75 providing guides for said bolt, means normally projecting said bolt from said casing, and members oppositely inclined relatively to one another engaging said bevel portion when the bolt is projected to wedge said bolt between said guides and said members.

29. A latch comprising a mounting provided with a guide passage, a latching member movable in said guide passage, said latching member provided with a bevel portion, and abutment means 85 engaging the bevel portion of said latching member when the latching member is projected to clamp said latching member against all lateral movement in said passage.

30. A latch comprising a mounting provided with a guide passage, a latching member movable in said guide passage, said latching member provided intermediate its 95 ends with a beveled or inclined portion, and abutment means in said passage inclined longitudinally of the latching member, said abutment means engaging the beveled or inclined portion of the latching member when the latching member is projected to clamp 100 said latching member against all lateral movement in said passage.

31. A latch comprising a latching member, a mounting for said latching member, said mounting formed to provide oppositely 105 inclined guides for said latching member, and means operable when the latching member is projected to move said latching member into engagement with said guides to clamp the latching member against lateral movement.

32. A latch comprising a latching member provided with an inclined or beveled portion intermediate its ends, a mounting 115 for said latching member, said mounting formed to provide oppositely inclined guides for said latching member, and abutment means engaging the inclined or beveled portion of the latching member when the latching member is projected to force said latching member into engagement with said guides to clamp the latching member against lateral movement.

33. A latch comprising a latching member provided with an inclined or beveled portion 125 intermediate its ends, a mounting for said latching member, said mounting formed to provide oppositely inclined guides for said latching member, and oppositely inclined abutment members engaging the inclined or 130

beveled portion of the latching member when the latching member is projected to force said latching member into engagement with said guides, said latching member being clamped against lateral movement between said abutment members and said guides.

34. A latch comprising a latching member formed from a single piece of sheet metal 10 bent to provide an inclined or beveled portion intermediate the ends of said latching member, a mounting for said latching member, said mounting formed to provide oppositely inclined guides for said latching member, and abutment means engaging the inclined or beveled portion of the latching member, when the latching member is projected to force said latching member into engagement with said guides to clamp the 20 latching member against lateral movement.

35. A latch comprising a channel-shaped latch bolt having a web portion and depending sides or flanges, said bolt provided with a beveled or inclined portion intermediate 25 its ends, a mounting for guiding said bolt, said mounting provided with a projection having oppositely inclined portions extending between the sides or flanges of said channel-shaped bolt, and abutment means engaging the beveled or inclined portion of said bolt when the bolt is projected to force said bolt into engagement with said projection to clamp the bolt against lateral movement.

36. A latch comprising a channel-shaped 35 latch bolt having a web portion and depending sides or flanges, said bolt provided with a beveled or inclined portion intermediate its ends, a mounting for supporting and guiding said bolt, said mounting provided 40 with a projection having oppositely inclined portions extending between the sides or flanges of said channel-shaped bolt, and abutment members provided with oppositely inclined portions engaging the beveled or inclined portion of the bolt when the bolt is projected to wedge said bolt between said abutment members and to force the bolt into engagement with said projection to clamp the bolt against lateral movement.

50 37. A latch comprising a channel-shaped latch bolt having a web portion and depending sides or flanges formed from a single piece of sheet metal, said bolt bent to provide a beveled or inclined portion intermediate its ends, a mounting for supporting and guiding said bolt, said mounting provided with a projection having oppositely inclined portions extending between the sides or flanges of said channel-shaped bolt, and abutment members provided with oppositely inclined portions engaging the beveled or inclined portion of the bolt when the bolt is projected to wedge said bolt between said abutment members and to force the bolt into

engagement with said projection to clamp the bolt against lateral movement.

38. A latch comprising a channel-shaped latch bolt having a web portion and depending flanges, the flanges at one end of said bolt being inclined relatively to each other 70 so that the edges of said flanges form bearing surfaces inclined transversely of the bolt, said bolt provided with a beveled or inclined portion extending longitudinally of the bolt intermediate its ends, a mounting 75 for supporting and guiding said bolt, said mounting provided with a projection having inclined portions extending between the inclined portions of the bolt flanges and cooperating therewith, and abutment members 80 provided with oppositely inclined portions engaging the longitudinally beveled or inclined portion of the bolt when the bolt is projected to wedge said bolt between said abutment members and to force the bolt into 85 engagement with said projection to clamp the bolt against lateral movement.

39. A latch comprising a channel-shaped latch bolt having a web portion and depending sides or flanges, said bolt provided with a beveled or inclined portion intermediate 90 its ends, a mounting for supporting and guiding said bolt, spring means for projecting said bolt, the web at one end of the bolt being cut away to form a socket for receiving one end of said spring means, and abutment means engaging the beveled or inclined portion of said bolt when the bolt is projected to clamp said bolt against lateral 95 movement.

40. A latch comprising a channel-shaped latch bolt having a web portion and depending sides or flanges formed from a single piece of sheet metal, said bolt provided with a beveled or inclined portion intermediate its ends, a mounting for supporting and guiding said bolt, means for retracting the bolt, said bolt provided with an integral lug or tongue forming a bearing surface for one side of the bolt, said lug or tongue also forming an abutment adapted to be engaged by the retracting means when the bolt is retracted, and abutment means engaging the beveled or inclined portion of said bolt when the bolt is projected to clamp said bolt against lateral movement.

41. A latch comprising a mounting provided with a guide passage, a latching member movable in said guide passage, said latching member provided intermediate its ends with a beveled or inclined portion, means for projecting said latching member, means for retracting said latching member, resilient means normally holding said retracting means out of engagement with said latching member when the latching member is fully projected, and abutment means engaging said beveled or inclined portion of

the latching member when the latching member is projected to clamp said latching member against lateral movement.

42. A latch comprising a mounting provided with a guide passage, a latching member movable in said guide passage, said latching member provided intermediate its ends with a beveled or inclined portion, and abutment means inclined laterally and lon-

gitudinally of the bolt, said abutment means 10 engaging the beveled or inclined portion of said latching member when the latching member is projected to clamp said latching member against lateral movement.

In testimony whereof I hereunto affix my 15 signature.

FRANCIS M. VANDERVOORT.
